UNITED STATES PATENT OFFICE.

GLENN S. WILLIAMSON, OF NEW YORK, N. Y., AND CHARLES E. MANDELICK, OF RIDGEFIELD PARK, NEW JERSEY, ASSIGNEES TO PUBLISHERS UTILITIES COMPANY, A CORPORATION OF NEW YORK.

MARGIN-REGULATING MECHANISM FOR WEB-ROLLS.

1,171,396.

Specification of Letters Patent.

Patented Feb. 8, 1916.

Original application filed August 5, 1911, Serial No. 642,544. Divided and this application filed January 21, 1915, Serial No. 3,591. Renewed November 1, 1915. Serial No. 59,148.

To all whom it may concern:

Be it known that we, GLENN S. WILLIAMSON and CHARLES E. MANDELICK, citizens of the United States, and residents, respectively, of New York, borough of Manhattan, county and State of New York, and Ridgefield Park, county of Bergen, State of New Jersey, have invented certain new and useful Improvements in Margin-Regulating Mechanism for Web-Rolls, of which the following is a specification.

This invention relates to web guiding mechanism and to margin-regulating mechanism for web rolls, and the subject-matter hereof constitutes a division of our application filed August 5th, 1911, Serial No. 642,544, now Patent No. 1,160,556, which application is directed more particularly to means for maintaining a uniform tension on the web, the same including a braking electric generator driven by the web.

The object of this invention is to produce a simple and effective mechanism whereby accurate axial adjustment of the web roll may be effected to keep the web running true and thereby preserve uniform margins.

A further object is to combine such mechanism with the connections for driving the generator, so as to produce a unitary apparatus that can be connected with and disconnected from one end of the web roll spindle, thus making possible a compact and advantageous arrangement and permitting ready replacement of the web roll and spindle.

A further object of the invention is to provide a simple and efficient mechanism whereby accurate adjustments of the web roll may be effected in printing presses so as to preserve uniform margins and to regulate the margins of the web with relation to a printing couple of the press.

To these ends the invention comprises the parts, improvements and combinations herein described and illustrated in their preferred forms and more particularly pointed out in the appended claims.

In the accompanying drawings showing the preferred embodiment of the invention: Figure 1 is a plan view, partly broken away and partly in section, showing the application of the invention to a printing-press, the cover being removed from the braking

and margin-regulating mechanisms; Fig. 2 is a side elevation of the mechanisms, parts 55 being in section; Fig. 3 is a horizontal section on an enlarged scale, the plane of the section intersecting the axis of the web roll spindle and the telescopic shaft clutch connected therewith, parts being shown in plan; 60 Fig. 4 is a sectional detail view; and Fig. 5 is a diagrammatic view illustrating wiring.

The numeral 6 indicates a press frame, 7 the web roll, and 8 the web roll spindle mounted in open bearings. 65

80 and 81 are the type roll and blanket roll of the printing couple.

The margin - regulating mechanism is preferably combined with the braking mechanism that maintains uniform tension 70 on the web, and both are preferably mounted on a base or support 9 which is movable toward and from the side of the press frame, preferably by being hinged thereto as shown at 10. The brake mechanism 75 shown is illustrated and described in detail in the aforesaid application and need not here be set forth with the same detail. It comprises an electric generator 11, the armature of which is driven by the roll 80 spindle 8 and the field of which is floating or rotatable so as to be turned by the torque of the armature. The field frame 12, as it turns, by means of a gear ring 13 which it carries, operates a suitable rheostat (not 85 shown) to cut resistance progressively into the armature circuit, so that the braking effect of the generator is diminished as the roll decreases in size and its angular velocity increases. Since the progressive introduction of resistance into the armature circuit diminishes the drag of the armature on the field, means are provided for opposing decreasing resistance to the turning of the field by the armature, an embodiment 90 of which means comprises a suitable cam 14 turned by the field frame through gears 15, 16, and acting on a flexible connection 17 to raise a lever 18 carrying a weight 19.

All of this is fully set forth in our prior 100 application, to which reference may be had for details.

The armature of the generator is driven from the spindle 8 by a clutch 20, a telescopic shaft 21, a gear 22 on the end of said 105 shaft, and a pinion 23 on the armature shaft

and meshing with said gear. The clutch 20 is preferably a magnetic clutch, and comprises a conical electromagnetic member 24 at the other end of the shaft and a concave 5 conical armature member 25 fixed to the end of the roll spindle. The coils 26 of the clutch are supplied with current from any suitable source by wires 27 passing through the shaft, which is preferably hollow for 10 the purpose. Means, not shown, are provided for opening and closing the circuit, so that the support 9 may be swung away from the spindle to permit a new roll and spindle to be placed on the spindle bearings 15 in place of an exhausted roll. The shaft 21 includes two telescopic sections 28, 29, which turn in suitable bearings 30, 31. The section 28 carries the gear 22 and does not move axially. The section 29 constitutes 20 an external sleeve which is slidable on the section 28 but is suitably connected therewith so that the two rotate together. The sleeve 29 is preferably connected with the clutch member 24 by universal joints which 25 compensate for any lack of exact axial alignment between the shaft sections 28, 29 and the spindle 8. To this end there is an angularly movable shaft section 32 which is connected with a flange 33 fixed to the sleeve 29 and to a plate 34 fixed to the clutch member 24, by means of universal joints 35, 36. Casing sections 37, 38 are likewise fixed to 30 the said flange and plate and have their opposed ends spherical and received by the concaved ends of casing sections 39, 40, the 35 opposed ends of which are cylindrical and received one within the other; and a spring 41 is confined between these last two sections and tends to hold this flexible part of the 40 shaft straight.

Means are provided for shifting the roll spindle 8 axially either electrically or by hand. The electrical means include a small electric motor 42, which is also carried by 45 the support 9 and is of a character suitable for running in either direction. It operates through the connections for driving the generator 11 and for connecting and disconnecting the same with the spindle. To this 50 end its shaft carries a worm 43, which meshes with a worm wheel 44, which in turn is mounted on the upper end of a vertical shaft 45 mounted in a bearing 46 on the support. The shaft 45 carries at its lower end 55 a bevel gear 47, which meshes with a bevel gear 48 on a screw shaft 49. The latter is disposed parallel to the shaft 21 and is journaled in suitable bearings 50, 51 mounted on the support 9. Its threads enter 60 a gage with a nut 52 pivoted to the end of a lever 53, which is fulcrumed at 54 on the support, the lever being slotted at this end because its free end is constrained by the screw to move in a straight line. Intermediate 65 its ends the said lever engages a

collar 55 on the slideable shaft section 29. Obviously any suitable shifting device may be employed in place of the lever 53.

Fig. 5 illustrates a form of wiring for starting and stopping the motor and causing it to run in either direction. Wires 56, 57 connect with the field coils, and wires 58, 59 with the armature brushes. When the switches R and L are in the positions shown, no current passes through the motor, which remains at rest. When the switch L is moved against the contact 60, current passes from the plus line wire by wire 61 through the field coils, from wire 57, to wire 62, thence by wire 59 to and through the armature in one direction, and by way of the wire 58, switch R and wire 63 to the minus main. With the switch L in the position shown and switch R in contact with 64, the current passes as before through the field coils, but is reversed through the armature, so that the motor runs in the reverse direction. Suitable means are provided for operating switches R and L. In the particular embodiment of the invention illustrated the switches R and L are operated manually. It will thus be seen that the motor may be operated to shift the web roll axially in either direction through a suitable reducing gearing acting upon certain of the connections for driving the braking generator.

The manual means for adjusting the web roll spindle is shown as comprising a horizontal shaft 65 journaled in a bearing 66 on the support 9, a hand wheel 67 on the outer end of this shaft, and a bevel gear 68 on its inner end meshing with the bevel gear 48 on the screw shaft 49.

Means are provided for permitting slip to occur in the connections between the motor 42 and the spindle 8, so that if by accident the spindle were shifted as far as it could go in either direction with the motor still running, no damage would result to the latter because the slip connection would yield. By locating this slip connection between the motor and the manual adjusting means, it also permits the spindle to be adjusted manually without turning the armature and without encountering the difficulty or impossibility of turning the worm 43 from the worm wheel 44. Preferably the slip connection is between the said worm wheel and the shaft 45. As shown, the worm wheel is mounted loosely on the upper end of the said shaft, but is normally frictionally coupled therewith by means of a spring 69 which presses the worm wheel downward against a friction member or collar 70 on the shaft.

What we claim as new is:

1. In a margin regulator for web rolls of printing presses, the combination with a roll spindle, a rotary shaft driven thereby, an electric motor acting upon said shaft for ad-

justing the web roll axially and circuits and contact devices for causing the motor to run in opposite directions.

2. A margin regulator for web rolls of printing presses, comprising the combination of a roll spindle, an electric motor for adjusting the roll spindle axially, a clutch for connecting and disconnecting said motor and the roll spindle and circuits and contact devices for causing the motor to run in opposite directions.

3. In a web roll apparatus for printing presses, the combination with a roll spindle, of an electric motor for shifting the same axially, and connections between said motor and the spindle including a frictional slip device.

4. In a web roll apparatus, the combination with a roll spindle, of means for adjusting the same axially comprising a rotary electric motor, and circuit changing means for causing the motor to rotate in either direction.

5. In a web roll apparatus, the combination with a roll spindle, of an electric motor, reducing gearing connections between said motor and spindle for moving the latter axially, and means including circuits and contact devices for causing the motor to run in opposite directions and for stopping the same.

6. The combination with a roll spindle, of a rotary member, a clutch connection between said member and the spindle, a shifting device engaging with said member to move the spindle endwise, a screw for operating said shifting device, and means for turning the screw.

7. Means for shifting a roll spindle axially, comprising an endwise movable member, a screw for adjusting and holding said member, manual means for operating said screw, an electric motor, and means including a frictional slip connection for driving said screw from said motor.

8. The combination with a frame for supporting a web roll spindle, a support movable relatively thereto, mechanism mounted on said support for adjusting the roll spindle axially, and a clutch for connecting and disconnecting said mechanism with the spindle.

9. The combination with a frame for supporting a web roll spindle, a support movable relatively thereto, an electric motor mounted on said support, means for causing said motor to run in either direction, a rotary member carried by said support, a clutch carried by said member for coupling it with the roll spindle, and connections whereby said motor shifts said member axially.

10. In a margin regulator, the combination with means for shifting a web laterally, a rotary electric motor for operating the web

shifting means and circuit changing means for causing the motor to rotate in either direction.

11. In a margin regulator for regulating the margins of a web with relation to a printing couple of the printing press, the combination of means for adjusting the web laterally, so as to adjust the margins with relation to the printing member of the couple, an electric motor for operating said web adjusting means and circuit changing means for causing the motor to run in either direction.

12. In a margin regulator, the combination with means for mounting a web roll, of a reversible electric motor connected to shift the roll axially, circuit-controlling means to cause the said motor to run in either direction, and manual means for shifting the web independently of the motor.

13. In a margin regulator, means for mounting a web roll, means for adjusting the same axially, a reversible electric motor having connections for operating said means, and a manual device adapted to operate said web-adjusting means independently of the motor.

14. In a margin regulator and in combination with means for supporting a traveling web, an electric rotary motor and connections whereby said motor may adjust the web laterally, different circuits through the motor adapted to energize the same to run in opposite directions, and means for controlling said circuits.

15. In a margin regulator and in combination with means for supporting a traveling web, an electric motor, means including a screw and nut whereby the said motor may adjust the web laterally, and circuit-controlling means for causing the motor to run in either direction.

16. In a margin regulator, the combination with means for mounting a web roll, of a screw and nut for adjusting said roll axially, an electric motor connected with one of said elements, and circuit-controlling means for causing said motor to run in either direction.

17. In a margin regulator, the combination of means for adjusting a web laterally, a reversible electric motor and controlling means for causing said web-adjusting means to operate in either direction, and means whereby said web-adjusting means may be operated manually.

18. In a margin regulator, the combination with means for supporting a traveling web, of a reversible electric motor, connections whereby said motor may shift the web laterally, and manual means for operating said connections independently of the motor.

19. In a margin regulating apparatus for regulating the margins of a web with rela-

tion to a printing couple, the combination of a roll spindle, a rotary electric motor, reducing gearing connections between said motor and spindle for moving the latter 5 axially and means including circuits and contacts for causing the motor to rotate in opposite directions.

20. In an apparatus for regulating the margins of a web with relation to a printing couple of a printing press, the combination of web supporting means, a means for shifting said web laterally, comprising a rotary electric motor, reducing gearing connections between said motor and the web for 10 shifting the latter sidewise and means including circuits and contact devices for causing the motor to rotate in opposite directions.

21. In a margin regulator for regulating 20 the margins of a web with relation to a printing couple of a printing press, the combination of means for adjusting the web laterally comprising a rotary electric motor, a laterally movable collar for shifting said 25 web supporting means, a member engaging said collar and reducing gearing connection between said motor and said member and means including circuits and contact devices for causing the motor to rotate in opposite 30 directions.

22. In a margin regulator for regulating the margins of a web with relation to a

printing couple of a printing press, the combination of means for adjusting the web laterally comprising a rotary electric motor, 35 web supporting means, a movable collar for shifting said web supporting means, a member engaging said collar, reducing gearing connections including a screw between said motor and said member and means including 40 circuits and contact devices for causing the motor to rotate in opposite directions.

23. In a margin regulator for regulating the margins of a web with relation to a printing couple of a printing press, the combination of means for adjusting the web laterally comprising a rotary electric motor, a roll spindle, a movable collar for shifting said roll spindle, a clutch between the collar and the roll spindle, a member engaging 45 said collar, reducing gearing connections including a screw between said motor and said member and means including circuits and contact devices for causing the motor to run in opposite directions so as to shift the web 50 laterally.

In testimony whereof, we have signed our names in the presence of two subscribing witnesses.
